UNITED STATES PATENT OFFICE.

CHARLES WILLMOTT, OF WOBURN SANDS, ENGLAND.

GOLF CLUB.

Application filed June 24, 1921. Serial No. 480,109.

To all whom it may concern:

Be it known that I, CHARLES WILLMOTT, subject of the King of Great Britain, residing at Aspley Road, Woburn Sands, Bedfordshire, England, have invented new and useful Improvements in and Relating to Golf Clubs; and I do hereby declare the following to be a full, clear, and exact description of the invention, such as will enable others skilled in the art to which it appertains to make and use the same.

This invention relates to golf clubs such as drivers and brassies of the kind provided with an inserted metal plate in the face of the clubhead.

The object of the present invention is to provide an improved construction by means of which a more perfect balance than hitherto is obtainable with a considerable reduction in the quantity of exposed lead or other substance usually employed as a weighting medium.

According to this invention the metal plate is provided with a rearwardly extending stem which is inserted within a transverse hole bored through the club head having a lead or other suitable liner serving as the primary weighting medium of the club. Final security may be effected by means of a nut which resides within an enlargement of the transverse hole and engages the outer extremity of the said stem. This enlargement is subsequently filled with lead or other suitable weighting material and finished off flush with the outside of the club head in the conventional manner.

In order that the invention may be clearly understood a practical example of the same will now be described by aid of the accompanying drawings in which:

Fig. 1 is an elevation of the club head looking towards the driving face of the same.

Fig. 2 is a plan of the same.

Fig. 3 is a section on the line 3-3 of Fig. 1.

Fig. 4 is a similar section but showing the club before assembly of the parts.

Fig. 5 is a rear elevation of the club head showing the lead filling covering the securing nut.

In the drawings *a* represents the head of the club and *b* the driving face of the same. This face is recessed as at *c* to accommodate the metal plate *d* whilst a transverse hole *e*

extends through the club head from this recess *c* to a circular enlargement or pocket *f* which opens out at the rear side of the club head.

The plate *d* is integrally or otherwise formed with a rearwardly extending stem *g* the outer extremity of which is screwed as at *h* for the reception of a locking nut *i*.

In assembly a lead liner *j* is first inserted in the hole *e* after which the stem *g* of the plate *d* is forced through the liner until such plate resides flush within the recess *c* after which the whole is pulled tightly into position by means of the nut *i*. The enlargement is then filled with lead as at *k* which filling is then finished off flush with the outside face of the club head.

The lead liner and filling are so proportioned as to effect the required weighting of the club.

It will thus be seen that the exposed area of the lead filling needs but to be small in comparison to the conventional filling the additional required weight being supplied by the lead liner *j*.

The lead liner may either be separately formed and inserted in the hole *e* as above-mentioned or the stem of the metal plate may be first positioned in the hole when the lead liner is formed by pouring the same at the same time as the filling *k* in the molten state around the stem and nut *i*. For this purpose pouring channels *l* shown dotted in Figs. 3, 4, and 5 are provided whereby the molten lead may pass around the nut and so into the hole *e*.

Having now particularly described and ascertained the nature of my said invention and in what manner the same is to be performed, I declare that what I claim is:

1. A golf club comprising in combination a head, an aperture extending transversely through said head and substantially parallel to its base and having an enlargement at both ends, a headed bolt located in said head with its stem extending through said aperture and its head disposed within one of said enlargements, a lead sleeve surrounding said stem and fitting within, and of the same length as said aperture, said sleeve serving as the primary weighting medium for the club, a nut located in said further enlargement engaging the end of said stem and serving to hold said bolt in position, and a filling of lead in the enlargement con-

taining the nut, said filling surrounding said nut and serving as the secondary weighting medium for the club.

2. A golf club comprising in combination a head, an aperture extending transversely through said head and substantially parallel to its base, an enlargement at both ends of said aperture, a headed bolt located in said head with its stem extending through said aperture and its head disposed within one of said enlargements, a lead sleeve surrounding said stem and fitting within and of substantially the same length as, said aperture, said sleeve serving as the primary weighting medium for the club, a nut located in said further enlargement engaging the end of said stem and serving to hold said

bolt in position, and a filling of lead in the enlargement containing the said filling surrounding said nut and serving as the secondary weighting medium for the club, grooves in the end of said aperture effecting a communication between the same and one of the enlargements whereby lead in a molten state may be poured into the aperture when the bolt and nut are in position so as to form the sleeve by moulding.

In witness whereof I have signed this specification in the presence of two witnesses.

CHARLES WILLMOTT.
